UNITED STATES PATENT OFFICE.

BRUCE H. CARNAHAN, HENRY M. WILLIAMS, AND HENRY W. BERTRAM, OF INDIANAPOLIS, INDIANA.

AUTOMATIC FEEDING ATTACHMENT FOR GLUE-JOINTERS.

1,267,511.

Specification of Letters Patent. Patented May 28, 1918.

Application filed March 13, 1916. Serial No. 83,968.

To all whom it may concern:

Be it known that we, BRUCE H. CARNAHAN, HENRY M. WILLIAMS, and HENRY W. BERTRAM, citizens of the United States of America, residing at Indianapolis, in the county of Marion and State of Indiana, have invented certain new and useful Improvements in Automatic Feeding Attachments for Glue-Jointers, of which the following is a specification, reference being had thereto to the accompanying drawing.

This invention relates to an attachment for wood working machines, especially known or used as an attachment for a glue jointer, and has for its object the production of a simple and efficient attachment which may be readily applied to, made a part of, or built into different machines for conveniently turning over the pieces of material which are being worked upon, thereby eliminating one or more operators previously found necessary to employ in order to accomplish the desired results.

A still further object of this invention is the production of a simple and efficient means which may be attached to a glue jointer wherein the lumber may be automatically turned over, or in other words reversed for the next operation of the machine without the necessity of requiring an operator to manually lift the lumber and turn the same to the desired position.

Other objects and advantages of the present invention will appear throughout the following specification and claims, and it should be understood that many detail changes may be employed without departing from the spirit of the invention so long as the construction is covered by the appended claims.

In the accompanying drawings:—

Figure 1 is a side elevation of a jointer showing the attachment applied thereto.

Fig. 2 is a top plan view of a portion of the jointer having the attachment applied thereto.

Fig. 3 is a section taken on line 3—3, of Fig. 2.

Fig. 4 is a section taken on line 4—4, of Fig. 2.

Fig. 5 is a section taken on line 5—5, of Fig. 2.

Fig. 6 is a section taken on line 6—6, of Fig. 2.

Fig. 7 is an enlarged longitudinal section taken on line 7—7, of Fig. 2.

Fig. 8 is a bottom plan view of the clutch mechanism shown in Fig. 7.

Fig. 9 is a bottom plan view of the clutch mechanism which is adapted to operate the shifting arms.

Fig. 10 is a section taken on line 10—10, of Fig. 2.

Fig. 11 is a section taken on line 11—11, of Fig. 10.

Fig. 12 is a section taken on line 12—12, of Fig. 10.

Fig. 13 is a section taken on line 13—13, of Fig. 10.

Fig. 14 is a side elevation of the sliding clutch jaw used in connection with the structure shown in Fig. 10.

Fig. 15 is a section taken on line 15—15, of Fig. 7.

Fig. 16 is a section taken on line 16—16, of Fig. 2.

Fig. 17 is an enlarged longitudinal section through one of the roller operating shafts showing the manner in which the driving beveled gear is applied to the shaft.

Fig. 18 is a detail perspective view of the upper end of one of the link arms adapted to operate the clutch for controlling the operation of the shifting arms.

By referring to the drawings it will be seen that 1 designates the body of the glue jointer or may be substituted by any other suitable wood working machine to which the body of the attachment 2 is applied. For the purpose of clearness this attachment will be referred to hereinafter as the lumber reversing attachment, and by carefully considering Fig. 2 which shows the attachment in top plan and in considerable detail, it will be seen that a bed plate 3 is employed, which bed plate is secured to the machine 1 by means of the straps 4 of suitable construction. It should be understood, that a driving shaft 5 passes through the machine 1 and carries at its upper end a pulley 6.

of suitable construction and as is employed upon the usual type of a glue jointed machine. The lower end of the driving shaft 5 is provided with a squared neck 7, which squared neck 7 fits in a socket 8 of the friction clutch 9. This friction clutch 9 comprises an upper section which is provided with a depending end 10 having a depending pintle or bolt member 11 projecting therefrom upon which is mounted a coil spring 12. A cup 13 is carried by the lower end of the bolt member 11, and a nut 14 is threaded upon the lower end of this bolt 11 for the purpose of permitting the tightening of the tension of the spring 12. The lower end of the spring 12 fits in the cup-shaped member 13 as illustrated in Fig. 5 of the drawings. An auxiliary section 15 of the friction clutch is keyed to the depending end 10 so as to be locked in rotary engagement therewith. A cap 16 is held in frictional engagement with the lower section 15 of the friction clutch 9. A plurality of fiber or other suitable disks 17 are carried by the adjacent faces of the upper and lower sections of the friction clutch, which disks 17 are adapted to frictionally engage the upper and lower faces of the sprocket wheel 18 mounted thereon. This sprocket wheel 18 is loosely mounted upon the depending portion 10 as illustrated in Fig. 5, but it should be understood that the spring 12 will frictionally hold or lock the sprocket wheel 18 in engagement with the friction clutch. Under undue pressure, however, it should be understood that to prevent the breaking of other parts of the machine, the yieldable engagement of the clutch with the sprocket wheel 18 will permit the rotation of the sprocket independent of the clutch 9 or vice versa, depending, of course, upon the relation of the pressure to the respective portions of the machine.

It should be understood that the bed plate 3 of the reversing attachment is bolted or otherwise secured to the main portion of the machine 1 by means of the bolts 19, and a driving sprocket 20 is carried by the bed plate 3 upon a shaft 21. A sprocket chain 22 passes around this sprocket 20 and also around the driven sprocket 18 as is clearly illustrated in Figs. 2, 3 and 5 of the drawings. The lower end of this shaft 21 carries a beveled gear 23, which beveled gear 23 meshes with a beveled gear 24 carried by a driving shaft 25, the driving shaft 25 extending longitudinally of the bed plate 3 and being supported in a suitable manner by means of suitable hangers which may be provided therefor. A plurality of driving beveled gears 26 are carried by the shaft 25, and these beveled gears 26 mesh with beveled gears 27 carried by the diagonally extending shafts 28 as clearly illustrated in Figs. 3 and 4 of the drawings. These shafts

28 are provided with universal joints 29 at the upper ends thereof, which universal joints engage stub shafts 30 for driving vertically extending conveyer rollers 31 carried by the adjustable frame 32. One of the conveyer rollers 31 is provided with a beveled gear 33 upon the lower face thereof which engages the beveled gear face 34 of the horizontal roller 35. This horizontal roller 35 is placed near the forward end of the bed plate 3, or in other words is placed adjacent the main machine 1 so as to facilitate the entrance of the lumber from the attachment to the main machine.

The frame 32 is slidably mounted upon a pair of trackways 36 formed upon the bed plate 3, and is yieldably held in its proper position by means of the coil springs 37 mounted upon an adjusting rod 38 passing through a journal or bracket 39. It should be understood that the tension of this spring 37 may be regulated by means of the bolt 40 when so desired.

A plurality of these frames 32 are positioned at proper points along the bed plate 3 to suit the convenience of the operator and are similarly constructed to the one previously described, with the exception that the horizontal roller 35 is eliminated, and is only carried by one of the frames 32 as illustrated clearly in the drawings.

It should be understood that the lower ends of the shafts 28 are keyed as indicated in Fig. 17 to the beveled gears 27 so as to permit the longitudinal adjustment of the shafts 28 to suit the different widths of lumber which are adapted to pass over the attachment and engage the vertically extending rollers 31.

A shifting arm operating shaft 41 is carried upon the bottom of the bed plate 3, and this shaft 41 carries a plurality of arc-shaped shifting arms 42, which arc-shaped shifting arms 42 are adapted to work through the transversely extending slots 43 formed in the bed plate 3. These arms 42 are arranged so as to extend substantially diametrically opposite to each other, and are preferably arranged in pairs as clearly illustrated in Figs. 2 and 4 of the drawings. A driven sprocket 44 is carried by the shaft 41, and this sprocket 44 receives a sprocket chain 45, which sprocket chain 45 also passes over a sprocket wheel 46 carried by the shaft 25 and continually drives the sprocket 44, which sprocket is loosely mounted upon the shaft 41, as well as the clutch section 47. An auxiliary clutch section 48 is keyed to the shaft 41 and is slidably mounted thereon and is adapted to engage the clutch section 47 for the purpose of rotating the shaft 41 at certain intervals as will be hereinafter fully described.

The bed plate 3 is provided with a longitudinally extending groove 49 which is sub-

stantially centrally arranged upon the bed plate 3 and communicates with the transversely extending slots 43.

A bar 50 is suspended below the bed plate 3, and upon this bar 50 is pivotally mounted a plurality of link arms 51. These link arms 51 are pivotally connected at their lower ends to a connecting link 52. The upper end of each link arm 51 is provided 10 with a cross bar 53 which is of sufficient length to fit in the slot 49 between the shifting arms 42 as illustrated in Figs. 2 and 3 of the drawings. An adjustable stop 54 is adapted to be secured to one of the bars 53 and constitutes an abutment against which the lumber is adapted to fit for the purpose of slightly moving the bar 53 sufficient to swing the clutch throwing arm or link 55. This clutch throwing arm or link 55 engages 20 the sliding clutch member 48 for throwing the same into engagement with the clutch portion 47, thereby permitting the rotation of the shaft 41. The clutch portion 48 is provided with a projecting lug 56 which is adapted to fit in one of the sockets 57 formed in the journal 58. A coil spring 59 is carried by the shaft 41 and is adapted to normally hold the clutch section 48 out of engagement with the clutch section 47.

30 By referring to Fig. 11 it will be seen that two sockets 57 are employed upon the journal 58, and it will be further understood that as soon as the pressure upon the lug 56 is released, which by the way will only be 35 for an instant, the clutch throwing arm 55 will again be free. As the lug 56 travels over the face of the journal 58, the shaft 41 will rotate for one-half of a revolution, whereupon the lug 56 coming in contact with 40 one of the sockets 57 will permit the spring 59 to retract the shaft 41 and draw the clutch section 48 out of engagement with the clutch section 47. It should be understood, however, that a piece of lumber is fed 45 across the shifting arms 42, and as the shaft 41 makes one-half a revolution, the piece of lumber or board marked A in Fig. 4 will be shifted from its position shown in full lines by the movement of the arms 42 to the 50 position shown in dotted lines marked B in Fig. 4. As the arms 42 continue to rotate to the position shown in full lines, the turn-over arms 60 will be forced from the dotted line position to the full line position, there- 55 by causing the turn-over arm shaft 61 to slightly rotate, and by so rotating, the clutch section 62 will be forced outwardly into engagement with the continuously rotating clutch section 63, thereby permitting the 60 shaft 61 to rotate for one-fourth of a revolution. This is possible in view of the fact that the clutch section 62 is provided with a projecting lug 64 adapted to fit in one of the notches 65 formed in the bearing 66.

65 Attention is particularly invited to Fig. 15

which shows the arrangement of the notches 65, there being four notches extending at right angles to each other in place of the two notches as previously described in connection with Fig. 11. It should be understood that the slight rotation of the shaft 61 due to the pressure of the plank or strip of lumber B against the turn-over arm 60 will merely be sufficient to raise the lug 64 out of engagement with one of the notches 65 for 70 throwing the clutch section 62 into engagement with the clutch section 63, the clutch then moving the shaft 61 a fourth of a revolution. A coil spring 67 is carried by the shaft 61 and is adapted to normally hold 75 the clutch section 62 out of engagement with the clutch section 63. A sprocket wheel 68 is loosely mounted upon the shaft 61, and this sprocket wheel 68 is driven by means of a sprocket chain 69 which also passes over a 80 sprocket wheel 70 indicated in dotted lines in Fig. 2 and also indicated in Fig. 3.

It should be understood that the plank indicated at A is standing upon one of its side edges, and the arms 42 will throw this 90 plank A to a horizontal position so as to lie upon one of its sides. However, when the fingers of the turn-over arms 60 which extend at right angles to each other engage the plank B and the shaft 61 is rotated for 95 a fourth of a revolution, the plank B will be turned up upon its opposite side edge to that illustrated in full lines in Fig. 4, thereby placing the plank or piece of lumber in position for jointing upon its opposite edge 100 upon its return to the jointing machine. It should be understood that the roller 35 will assist in forcing the plank or piece of lumber into the jointer, and that the rollers 31 will also assist in moving the plank longitudinally of the attachment illustrated.

It should be further understood that when it is so desired the adjustable stop 54 may be transferred from one of the head portions 53 to any of the others to suit the length of 110 pieces of lumber which are being worked.

The operation of the machine is as follows:—

A piece of lumber which we will refer to as a plank is fed from the jointing machine 115 through the passage or trackway 71 and engages the abutment 54 which is illustrated upon the last link 51. This will shift the clutch section 48 into engagement with the clutch section 47 and by being so shifted, 120 the shaft 41 will rotate for one-half a revolution thereby throwing the plank A shown in full lines from a vertical to a horizontal position indicated in dotted lines by the letter B. After this operation and as the arms 125 42 are completing their one-half revolution, the plank B will bear against one series of the fingers of the turn-over arms 60 and bring the same from a partially inclined to a vertical position, that is to say from the 130

dotted line position to the full line position. This slight movement will be sufficient to throw the clutch section 62 into engagement with the clutch section 63, whereupon the 5 shaft 61 will be rotated for a fourth of a revolution as previously described. The plank will then be entirely inverted, and will then be returned over the roller 35 into the channel or trackway 72 of the machine 1.

10 It should be understood that the planks will feed through the passage or track-way 71 upon its edge and as the fingers 42 are swung, the plank will be thrown upon its side as shown in Fig. 4 due to the fact that 15 the edge is very narrow and when pressure is brought to bear upon the side of the plank, the same will naturally tilt or flop over. The plank will be shifted to the side of the machine and will be engaged by the 20 turn-over arms 60 whereupon the plank will be again rested upon its opposite edge thereby entirely inverting the plank.

Having thus described the invention, what is claimed as new is:—

25 1. A device of the class described comprising a body, means for engaging a plank and moving the same from a vertical to a horizontal position, and means for turning said plank from a horizontal to a vertical position whereby a plank may be entirely inverted to rest upon its opposite side edge.

30 2. An attachment for a wood working machine for inverting a piece of material delivered from said machine without the aid of an operator comprising a body, shifting means carried by said body, means adapted to be engaged by a piece of material for throwing said shifting means into operation, and turn-over means carried by 35 said body and adapted to raise a strip of material from a horizontal to a vertical position.

40 3. An attachment of the class described comprising a frame, said frame provided with a bed plate, a plurality of turn-over arms carried by said bed plate, shifting arms carried by said frame, driving means, tripping means adapted to throw said driving means into engagement with said 45 shifting arms when said tripping means is engaged by a piece of material, and turn-over means coöperating with said shifting arms for changing a piece of material from resting upon its side to rest upon the edge.

45 5. A machine of the class described comprising a frame, shifting arms carried by said frame, a turn-over arm supporting shaft carried by said frame, turn-over arms carried by said supporting shaft, 50 clutch means coöperating with said shaft, tripping means for throwing said clutch means to an operative position, means for causing the rotation of said shaft one-half of a revolution, and said turn-over arms co- 55 operating with said shifting arms whereby 60

said shifting and turn-over arms will entirely invert a piece of material fed through said machine.

5. A machine of the class described comprising a base plate, shifting arms carried thereby, means for swinging said shifting arms, a second shaft, a plurality of turn-over arms carried by said second shaft, a clutch carried by said second shaft, and said clutch adapted to be thrown into engagement by the slight rotation of said turn-over arms whereby the shaft supporting said turn-over arms may be rotated for one-fourth of a revolution.

6. A machine of the class described comprising a bed plate, a turn-over arm supporting shaft, a shifting arm supporting shaft, a plurality of oppositely extending arc-shaped shifting arms carried by said last mentioned shaft, a plurality of angularly extending turn-over fingers carried by said first-mentioned shaft, tripping means for throwing said shifting arm supporting shaft into an operative position whereby said shifting arms will be swung for one-half of a revolution, said shifting arms adapted to throw a piece of material upon its side from its edge and adapted to press said piece of material against one of said fingers of said turn-over arms thereby rotating said first-mentioned shaft slightly whereby said first-mentioned shaft may be thrown to an operative position for permitting said first-mentioned shaft to rotate for one-fourth of a revolution.

7. A machine of the class described comprising a bed plate, a turn-over arm supporting shaft, a shifting arm supporting shaft, a plurality of oppositely extending arc-shaped shifting arms carried by said last-mentioned shaft, a plurality of angularly extending turn-over fingers carried by said first-mentioned shaft, tripping means for throwing said shifting arm supporting shaft into an operative position whereby said shifting arms will be swung for one-half of a revolution, said shifting arms adapted to throw a piece of material upon its side from its edge and adapted to press said piece of material against one of said fingers of said turn-over arms thereby rotating said first-mentioned shaft slightly whereby said first-mentioned shaft may be thrown to an operative position for permitting said first-mentioned shaft to rotate for one-fourth of a revolution, and means for returning said piece of material toward the entrance end of said bed plate.

8. A machine of the class described comprising a bed plate, a turn-over arm supporting shaft, a shifting arm supporting shaft, a plurality of shifting arms carried by said last-mentioned shaft, a plurality of turn-over fingers carried by said first-mentioned shaft, clutch means carried by each

shaft, tripping means coöperating with said clutch means of said last-mentioned shaft for causing the swinging of said shifting arms when said tripping means is actuated 5 for throwing a piece of material upon its side, said material having entered upon its edge, said piece of material adapted to be thrown against one of said turn-over fingers and said shifting fingers adapted to press 10 said piece of material against said turn-over fingers for swinging one of said turn-over fingers to a perpendicular position, whereby said first-mentioned shaft will be slightly rotated for throwing said clutch carried thereby to an operative position whereby 15 said shaft will be rotated for one-fourth of a revolution, and means for normally driving said clutch mechanism.

9. A machine of the class described comprising a bed plate, a friction driving mechanism, a chain coöperating with said friction driving mechanism, an operating shaft, means for driving said operating shaft through the medium of said chain, a shifting arm supporting shaft, a turn-over arm supporting shaft, a clutch carried by each shaft, said clutch of said shifting arm supporting shaft provided with a pair of notches formed therein, said clutch comprising 20 a pair of clutch sections, one of said clutch sections provided with a lug adapted to fit in said notches, yieldable means for normally holding said lug in said notches, tripping means for slightly rotating said 25 sliding section of said clutch for throwing said sliding section into engagement with the stationary section of said clutch whereby said first-mentioned shaft will be rotated for swinging said shifting arms for one-half of a revolution, said lug upon said 30 clutch adapted to engage said notches when rotated for one-half of a revolution whereby said sliding section of said clutch may be thrown to an inoperative position at each 35 half revolution of said first-mentioned shaft, and said shifting arms adapted to engage a piece of material and press the same in engagement with said turn-over arms for slightly rotating the same and throwing said 40 clutch carried thereby to an operative position whereby said turn-over arm supporting shaft will be rotated for one-fourth of a revolution.

10. A machine of the class described comprising a bed plate, means for inverting a piece of material passing thereover, return rollers adjustably mounted upon said bed plate and adapted to facilitate the return of 45 a piece of material toward the feeding end 50 of said bed plate, tracks carried by said bed plate, a frame supporting each feeding roller and slidably mounted upon said tracks, and yieldable means for normally urging said frame toward a piece of material 55 adapted to be engaged thereby.

11. A machine of the class described comprising a bed plate, means for inverting a piece of material passing thereover, return rollers adjustably mounted upon said bed plate and adapted to facilitate the return of 60 a piece of material toward the feeding end of said bed plate, tracks carried by said bed plate, a frame supporting each feeding roller and slidably mounted upon said tracks, yieldable means for normally urging 65 said frame toward a piece of material adapted to be engaged thereby, and means for regulating the tension of said yieldable means.

12. A machine of the class described comprising a bed plate, means for inverting a piece of material passing thereover, return rollers adjustably mounted upon said bed plate and adapted to facilitate the return of 70 a piece of material toward the feeding end of said bed plate, tracks carried by said bed plate, a frame supporting each feeding roller and slidably mounted upon said tracks, yieldable means for normally urging 75 said frame toward a piece of material adapted to be engaged thereby, and means for regulating the tension of said yieldable means.

13. A machine of the class described comprising a bed plate, means for inverting a piece of material passing thereover, return rollers adjustably mounted upon said bed plate and adapted to facilitate the return of 80 a piece of material toward the feeding end of said bed plate, tracks carried by said bed plate, a frame supporting each feeding roller and slidably mounted upon said tracks, yieldable means for normally urging 85 said frame toward a piece of material adapted to be engaged thereby, means for regulating the tension of said yieldable means, one of said feeding rollers provided with a beveled gear upon the lower end thereof, a horizontal feeding roller provided with a beveled gear upon the lower end thereof, a horizontal feeding roller provided with a bevel- 90

95 ed gear adapted to mesh with said first-mentioned beveled gear and adapted to engage the lower edge of a piece of material adapted to pass thereover.

14. A machine of the class described comprising a bed plate, means for inverting a piece of material adapted to pass thereover, a plurality of link arms, a supporting bar, said link arms pivotally secured to said supporting bar, a link connecting the lower ends 100

105 110 115 120 125 130

of said link arms, a sliding clutch, a clutch throwing arm connected to said link and engaging said clutch for throwing said clutch to an operative position, each link arm provided

5 with a head, and a detachable stop adjustably connected to one of said heads for facilitating the throwing of said clutch arm

when a piece of material abuts against said stop.

In testimony whereof we hereunto affix 10 our signatures.

BRUCE H. CARNAHAN.
